CLAIM

The ornamental design for a saw fence stop assembly, as shown and described.

DESCRIPTION

FIG. 1 is a perspective view of a saw fence stop assembly as taken from the front, right side and top thereof;

FIG. 2 is a front view thereof;

FIG. 3 is a rear view thereof;

FIG. 4 is a side view thereof (as taken from the left side of FIG. 2);

FIG. 5 is a side view thereof (as taken from the right side of FIG. 2);

FIG. 6 is a top view thereof;

FIG. 7 is a bottom view thereof; and,

FIG. 8 is a perspective view thereof as taken from the back, left and bottom thereof.

The broken lines are for the purpose of illustrating portions of the saw fence stop assembly and form no part of the claimed design.

1 Claim, 8 Drawing Sheets
